UNITED STATES PATENT OFFICE

JAMES F. GEARY, OF SALT LAKE CITY, UTAH

REAGENT FEEDER

Application filed December 1, 1925. Serial No. 72,595.

The present invention relates to reagent feeders and more particularly to feeders for delivering predetermined quantities of reagents at regular intervals.

5 The principal object of the present invention is to provide a reagent feeder which is adapted to deliver accurately determined quantities of one or more reagents and which may be readily adjusted to vary the rates or 10 amounts of delivery of the various reagents separately or with relation to one another.

With this and other objects in view, as will hereinafter appear, the present invention consists in the reagent feeder hereinafter described and particularly defined in the claims.

In the accompanying drawings, Figure 1 is 15 a front elevation of a reagent feeder embodying the features of the present invention; and Fig. 2 is a sectional elevation of the apparatus shown in Fig. 1.

The illustrated embodiment of the invention consists of a reagent feeder comprising a plurality of tanks 4 from which predetermined quantities of reagents are delivered by 20 means of reciprocating buckets indicated generally at 6. The tanks are supported in a framework 8 mounted on a concrete foundation 10. The level of liquid in each tank is maintained constant by means of a float 12 connected with any suitable form of valve mechanism. Secured to the framework are a plurality of bucket guides 14, one of which extends into each tank. Each guide includes a pair of tracks 16 vertically disposed within 25 and extending slightly above the top of the tank and curved at 17 into a horizontal portion 18 directly above a spout 20 within which the contents are to be discharged. The bucket 6 is provided with an integral ear 22 to receive a stud 24, which is received between the pair of tracks 16. Above the stud 24 the bucket is provided with an extended lip 26 over which the contents pass in being discharged into the spout 20. The bucket is pivotally mounted on a support 28 which is 30 adapted to slide freely over a rod 30 extending into the tank and secured between the bottom of the guide member 14 and a part of the framework. Upon vertical reciprocation 45 of the support 28 the bucket is first submerged

below the level of fluid in the tank, as shown in the dotted line position of Fig. 2, and is then raised, the bucket being guided by the tracks 14. As it nears the top of its stroke, the stud 24 in following the curved portion 55 of the track causes the bucket to be tipped into the position shown in full lines, to permit the flow of its contents into the spout 20, from which they are directed into a funnel 32 to be 60 conveyed to the desired point.

Reciprocating motion is imparted to the bucket support 28 by means of a pitman 34 pivotally connected at 36 to the bucket support and connected at its upper end with a crank disk 38 at the periphery of the latter. 65 The length of the pitman may be adjusted by a turn-buckle 40. The crank disk associated with each tank is supported on a stud 42 journaled in a bearing 44, and is urged by a coil spring 46 against a rotating friction 70 driving disk 50. Each crank disk 38 is provided with a counterweight 52 opposite the pitman connection. The various driving disks 50 associated with the different feeders 75 are splined on a driving shaft 53 which is journaled in bearings 54 and 56 and is rotated by a motor 58 through a worm drive. The shaft 53 may be supported at points intermediate its ends by pillow blocks 59. Each driving disk 50 has secured to it a grooved disk 60 80 within which is received a yoke 62, the yoke being retained in any adjusted position by a connection with a rod 64 which extends through the bearing block 44 and which is held in place by a set screw 66. By this means 85 any or all of the driving disks may be moved to any adjusted position with relation to the crank disks 38 to drive the latter at any desired speed. The speeds may be adjusted 90 relatively to one another without stopping the operation of the feeder so that the amounts of reagents delivered by the various buckets may be proportioned by controlling the rapidity of the dumping so as to give the correct 95 mixture of reagents desired to be used in the reaction.

The adjustment provided by the turn-buckle 40 on each pitman determines the amount of upward movement of the bucket 100 to dumping position. Thus by extending the

length of the pitman the bucket will be lifted to a less height and therefore the tipping of the bucket will be less, because the stud 24 will not have advanced so far around the curve 17 in the track 16. By this means the amount delivered by each dump may be controlled, to effect a further control of the proportion of the delivery of each reagent.

The formation of the bucket is such that 10 an accurate quantity of reagent is delivered at each dumping operation to the spout 20. Provision is made for preventing entrance of liquid into the spout except from the interior of the bucket, thus eliminating inaccuracy due to dripping of liquid from the exterior of the bucket. The ear 22, which is formed integral with the bucket, and the stud 24, which extends across the bucket directly below the lip, serve to catch any drops of liquid which tend to flow down the exterior side walls of the bucket and direct them back into the tank. Moreover, as shown in Fig. 2, the upper extremity of the lip when the bucket is in tilted position lies directly above the inner edge of the spout 20, so that all drippings from the bucket tend to drop outside the spout and the spout receives only the contents of the interior of the bucket. The curvature of the track at 17 is substantially on a radius, 20 of which the upper interior extremity of the spout 20 is the center, so that this condition obtains for any final position of the spout independent of the adjustment of the length of the pitman 34.

25 It will be observed that the positive reciprocating movement imparted to each bucket by its corresponding pitman provides not only for a positive submergence of the bucket but also for an accurate lifting of the bucket through an accurately predetermined stroke. The amounts of the various reagents discharged may be regulated by adjusting the lengths of the pitmen and speeds of the crank disks, the former adjustment serving 30 to regulate the quantity of each dump, and the latter to vary the interval between successive dumps. Accordingly, an accurate feed of predetermined relative quantities of the different reagents at regular timed intervals 35 is assured.

Having thus described the invention, what is claimed is:

1. A reagent feeder comprising a plurality of vertically reciprocating buckets each 40 adapted to feed a portion of the contents from a tank, means for tipping each bucket as it approaches the top of its stroke, means for reciprocating each bucket through a predetermined stroke, and means for relatively varying the speeds of the different buckets with respect to one another.

2. A reagent feeder comprising a plurality of tanks, a bucket for each tank adapted to 45 convey a portion of the contents from its corresponding tank, means for tipping each

bucket as it approaches the top of its stroke, means for reciprocating the buckets in timed relation to each other, and means for relatively varying the strokes of the buckets to vary the amount of tipping and the relative 50 discharge of their contents.

3. A reagent feeder comprising a plurality of tanks, a bucket for each tank, means for vertically reciprocating the buckets in timed relation to one another, means for tipping each bucket at the top of its stroke, and means for varying the relative positions of the various buckets with respect to one another.

4. A reagent feeder comprising a tank, a 80 bucket, a support on which the bucket is pivotally mounted, means for reciprocating the bucket comprising a crank and a pitman connecting the crank with the bucket, and adjustable means for rotating the crank at various speeds.

5. A reagent feeder comprising a tank, a bucket, a support on which the bucket is pivotally mounted, means for reciprocating the bucket comprising a crank and a pitman connecting the crank with the bucket, and adjustable means for rotating the crank at various speeds, a guide for the bucket having provision for tipping it as it approaches the top of its stroke and means for adjusting the length of the pitman to vary the amount of tipping of the bucket.

6. A reagent feeder comprising a plurality of tanks, a bucket associated with each tank, a support for each bucket, a guide for each bucket having provision for tipping the bucket as it approaches the top of its stroke, means for reciprocating each bucket comprising a plurality of cranks and pitmen connecting the cranks with the buckets, a rotatable shaft, means for driving the cranks from the shaft, and means for relatively adjusting the speeds of the various cranks.

7. A reagent feeder comprising a plurality of tanks, a vertically reciprocating bucket 110 associated with each tank for conveying therefrom a portion of its contents, a rotatable shaft, a friction disk for each bucket having a crank, a pitman connecting the crank with the bucket, and a rotatable shaft, 115 friction means on the shaft for driving the friction disks, and means for adjusting the friction means to vary the timing of the buckets and to vary the speeds at which the buckets are reciprocated.

8. A reagent feeder comprising a tank, a bucket guide extending into the tank, a bucket having an extended lip and a stud engaging with the guide and disposed below the lip, means for reciprocating and tipping the 125 bucket, a spout directly under the bucket when the latter is in tipped position, the stud serving to catch drippings from the exterior of the bucket and return them into the tank to prevent passage thereof into the spout.

9. A reagent feeder comprising a tank, a bucket, a guide for the bucket having provision for tipping the bucket at the top of its stroke, means for reciprocating the bucket through a predetermined stroke, means for adjusting the stroke to adjust the discharge of the bucket, and means for varying the speed of movement of the bucket. 5
10. A reagent feeder comprising a plurality of tanks, a bucket for each tank, means for reciprocating each bucket through a predetermined stroke and for tipping each bucket at the top of its stroke, means for relatively varying the strokes of the various buckets to adjust their discharges with respect to one another, and means for relatively varying the speeds of the buckets. 15
11. A reagent feeder comprising a tank, a vertically reciprocating bucket adapted to dip into the tank, a guide for the bucket having provision for tipping the bucket at the top of its stroke, means for reciprocating the bucket consisting of a reciprocating member movable through a stroke of unvarying length, and means for controlling the discharge of the bucket by varying the height to which the bucket is lifted independently of the length of the stroke of the reciprocating arm. 20
12. A reagent feeder comprising a tank, a spout, a vertically reciprocating bucket adapted to convey a portion of the contents of the tank to the spout, a guide for the bucket having provision for tipping the bucket as it approaches the top of its stroke, means for reciprocating the bucket through a stroke of unvarying length, and means for adjusting the height to which the bucket is lifted independently of the length of the stroke to vary the amount of tipping of the bucket. 30
13. A reagent feeder comprising a tank, a bucket having an extended lip, a spout, means for reciprocating and tipping the bucket for conveying a portion of the contents of the tank to the spout, the spout being directly under the extended lip of the bucket and having its rearward external surface substantially in vertical register with the lower external surface of the end of the lip when the bucket is in its tipped position whereby the spout will catch no drippings from the exterior of the bucket. 45
14. A reagent feeder comprising a tank, a bucket, means for reciprocating and tipping the bucket, and a spout to receive the contents of the bucket, the bucket having a projection on that side of the bucket which is lowest when the bucket is tipped to discharge its contents and adjacent the open end, the projection being offset vertically from the spout when the bucket is so tipped to cause the drippings from the exterior of the bucket to fall outside the spout. 55
15. A reagent feeder comprising a tank, a bucket, power actuating means having a
- uniform range of movement for causing the bucket to dip into the tank and to be raised therefrom, normally stationary devices for causing the bucket to tip while being raised, and mechanism for varying the relative positions of the bucket and said normally stationary devices to vary the tipping of the bucket to control the discharge of the contents thereof while maintaining uniform range of movement of the bucket. 70
16. A reagent feeder comprising a tank, a bucket, a crank, connections between the bucket and crank imparting a reciprocatory motion of uniform range to the bucket to cause it to convey material from the tank, normally stationary devices for tipping the bucket near the top of its stroke, and means for varying the relative positions of the bucket and said normally stationary devices to vary the tipping of the bucket to control the discharge of the contents thereof while maintaining uniform range of movement of the bucket. 75
17. A reagent feeder comprising a tank, a vertically reciprocating bucket, stationary means engaged by the bucket for tipping the same at the top of its stroke, mechanism for reciprocating the bucket including a continuously rotating member driven at uniform speed, and connections between said member and the bucket for reciprocating the bucket, constructed and arranged to impart a slow tipping movement to the bucket with a dwell when the bucket is at the limit of its tipping movement. 80
18. A reagent feeder comprising a tank, a bucket, a continuously rotating member driven at uniform speed, connections between said member and the bucket for vertically reciprocating the bucket, normally stationary devices engaged by the bucket for tipping the same at the top of its stroke, the connections being constructed and arranged to impart a slow tipping movement to the bucket with a dwell when the bucket is at the limit of its tipping movement, and mechanism for varying the relative positions of the bucket and said normally stationary devices to vary the degree of tipping of the bucket to control the discharge of the contents thereof. 100
19. A reagent feeder comprising a tank, a bucket, a rotatable crank, a pitman connecting the crank and the bucket for vertically reciprocating the latter, the bucket being at the limit of its vertical movements when the crank is passing dead centers, and a guide for the bucket having provision for tipping the bucket as the crank approaches a dead center and the bucket approaches the top of its stroke, said pitman having means for varying the amount of discharge from the bucket. 110
20. A reagent feeder comprising a tank, a bucket, a rotatable crank, a pitman connect- 120

ing the crank and the bucket for vertically reciprocating the latter, the bucket being at the limit of its vertical movements when the crank is passing dead centers, a guide for the 5 bucket having provision for tipping the bucket as the crank approaches a dead center and the bucket approaches the top of its stroke, and means for adjusting the length of the pitman to vary the amount of tipping of 10 the bucket.

21. A reagent feeder comprising a tank, a bucket, a support on which the bucket is pivotally mounted, a crank, a pitman connecting the crank with the bucket for reciprocating 15 the bucket, the bucket being at the limit of its vertical movements when the crank is passing dead centers, a guide for the bucket having provision for the tipping of the bucket as the tank approaches a dead center and 20 the bucket approaches the top of its stroke, and means for changing the vertical position of the bucket at dead center position of the crank to vary the amount of tipping of 25 the bucket and of the discharge of its contents.

22. A reagent feeder comprising a plurality of tanks adapted to contain various reagents, a reciprocating bucket for each tank for conveying and discharging predetermined 30 quantities therefrom, a driving shaft, and means driven from said shaft for actuating each bucket, said means having provision for adjustment to independently vary the 35 quantity of reagent discharged by each bucket in a given period of time.

23. A reagent feeder comprising a plurality of tanks adapted to contain various reagents, a reciprocating bucket for each tank for conveying and discharging predetermined quantities 40 therefrom, a driving shaft, actuating mechanism for each bucket, and adjustable connections between said shaft and said mechanisms to independently vary the speed of operation of said mechanisms.

45. 24. A reagent feeder comprising a plurality of tanks adapted to contain various reagents, a reciprocating bucket for each tank for conveying and discharging predetermined quantities therefrom, a driving shaft, and actuating mechanism at each bucket, 50 said mechanism having provision for independently varying the amount discharged from each bucket on each actuation thereof.

In testimony whereof I have signed my name to this specification.

JAMES F. GEARY.
